DESIGN FOR A STORE FRONT

Edwin Samuel Bender, Berkeley, Calif.

Application October 25, 1933, Serial No. 49,547

Term of patent 3½ years

To all whom it may concern:

Be it known that I, EDWIN SAMUEL BENDER, a citizen of the United States of America, and a resident of the city of Berkeley, county of Alameda, State of California, have invented a new, original, and ornamental Design for a Store Front, of which the following is a specification, reference being had to the accompanying drawing, forming a part hereof.

I claim:

The ornamental design for a store front, substantially as shown.

In testimony whereof, I have hereunto set my hand.

EDWIN SAMUEL BENDER.
